CARRYING CASE FOR A SOLDERING TOOL OR THE LIKE

Peter T. Schurman, Snyder, N.Y., assignor to W. R. Grace
& Co., New York, N.Y., a corporation of Connecticut

Filed June 7, 1965, Ser. No. 85,604

Term of patent 14 years

(Cl. D87—5)

FIG. 1.

FIG. 6.

FIG. 2.

FIG. 3.

FIG. 4.

FIG. 5.

FIGURE 1 is a perspective view of a partially open carrying case for a soldering tool or the like showing my new design;

FIGURE 2 is a plan view thereof in open position showing the outer surfaces of the bottom and top sections;

FIGURE 3 is a front elevational view thereof as it appears in closed position;

FIGURE 4 is a plan view thereof in open position showing the interiors of the top and bottom sections;

FIGURE 5 is a side elevational view thereof as it appears in closed position; and

FIGURE 6 is a rear elevational view thereof.

The dominant features of the design reside in the portions shown in solid lines, the broken line showing of the handle having been omitted from FIGURES 2-6 inclusive for convenience of illustration.

I claim:

The ornamental design for a carrying case for a soldering tool or the like, as shown and described.
